(57) **CLAIM**

The ornamental design for a bottle, as shown and described.

DESCRIPTION

FIG. 1 is a front elevational view of a transparent bottle showing our new design, the rear elevational view being a mirror image;

FIG. 2 is a side elevational view thereof, the opposite side view being a mirror image;

FIG. 3 is an enlarged top plan view thereof with the bottom plan view visible from the top plan view as it is shown in a transparent bottle; and,

FIG. 4 is an enlarged bottom plan view thereof with the top plan view visible from the bottom plan view as it is shown in a transparent bottle.

1 Claim, 4 Drawing Sheets
